UNITED STATES PATENT OFFICE.

CHARLES T. WESTLAKE, OF GRANITE, ILLINOIS.

CAR-BOLSTER.

SPECIFICATION forming part of Letters Patent No. 692,568, dated February 4, 1902.

Application filed June 20, 1901. Serial No. 65,247. (No model.)

To all whom it may concern:

Be it known that I, CHARLES T. WESTLAKE, of Granite, State of Illinois, have invented certain new and useful Improvements in 5 Car-Bolsters, of which the following is a full, clear, and exact description, reference being had to the accompanying drawings, forming a part hereof.

This invention relates to car-bolsters; and 10 it consists of the novel construction, combination, and arrangement of parts hereinafter shown, described, and claimed.

The object of this invention is to provide an improved car-bolster composed of I-beams 15 connected by means of side plates, having the bearings fixed upon the upper I-beam between the flanges, the advantages of which will be described below.

Figure 1 is a perspective view showing my 20 complete invention. Fig. 2 is a longitudinal section. Fig. 3 is an end view.

In the form shown in the drawings the bolster consists of the top 1, composed of an I-beam, the flanges 2 of which extend vertically 25 along the sides thereof. The bottom 3 also consists of an I-beam placed in same position as top 1, as clearly shown in Fig. 2. The top 1 and the bottom 3 are connected by means of the center plates 4 and the end brackets 5, 30 which are of usual construction and are rigidly attached to the flanges of the I-beams by means of rivets or other similar fastening devices. The central bearing-plate 6 is secured upon the top 1 and fits snugly between the 35 side flanges 2, whereby it is firmly retained in position by the flanges and bolts or rivets. The side bearings 7 are provided with laterally-extending bases 8, which rest upon the top 1, and the said bearings are also supported 40 between the flanges 2, whereby they are held in position and prevented from moving laterally and are secured by rivets or bolts. I-beams used by others for this purpose are placed with their webs vertical and their 45 flanges projecting horizontally. To provide for column-guides on bolsters of such construction, it is customary to notch the flanges of the beams to form same. It has been demonstrated that this does not provide sufficient bearing-surface, and it has become nec-

essary to attach separate pieces to provide such bearing-surface. Others, again, provide separate pieces for column-guides without notching the beams. When bolsters of this design are placed between cross-frames or 55 transoms of trucks, it is required that they have side chafing-pieces adjacent the center, and if constructed of I-beams with webs vertical it is necessary to attach separate pieces for the purpose, as the horizontally-projecting flanges of the beams have insufficient bearing-surface presented. Bolsters of this design also, as a general rule, require extra pieces at their ends on bottom to serve as 60 spring-seats to confine the springs. With my 65 design by placing the webs of I-beams in a horizontal position and connecting them by side plates the plates forming the connections also serve as column-guides and chafing-plates, and the downwardly-projecting flanges 70 of lower beam form seats to confine the springs.

I have shown and described a bolster which is composite and formed of a number of separable parts; but it is manifest that I may form 75 them in a single casting having the vertical flanges top and bottom. I do not desire to be limited to a composite bolster, since the variation mentioned would be only formal.

I claim—

1. A car-bolster, consisting of a top in the form of an I-beam and having upwardly and downwardly projecting flanges and bearings carried upon the top between the said flanges, and a bottom rigidly connected to the said top, substantially as specified.

2. A bolster, comprising a top and bottom both in the form of an I-beam and having upwardly and downwardly projecting flanges, side brackets connected to the top and bottom, 90 and bearings mounted upon the top between the said vertical flanges, substantially as specified.

In testimony whereof I affix my signature in presence of two witnesses.

CHARLES T. WESTLAKE.
